UNITED STATES PATENT OFFICE.

THOMAS BEAMONT ABBOTT, OF SALE, VICTORIA.

KNIFE-SCOURER.

SPECIFICATION forming part of Letters Patent No. 651,644, dated June 12, 1900.

Application filed January 10, 1900. Serial No. 993. (No model.)

To all whom it may concern:

Be it known that I, THOMAS BEAMONT ABBOTT, a subject of the Queen of Great Britain, residing at Sale, in the Province of Victoria, Australia, have invented certain new and useful Improvements in Knife-Scourers; and I do declare the following to be a full, clear, and exact description of the invention, such as will enable others skilled in the art to 10 which it appertains to make and use the same.

The invention relates to a knife-scourer.

The object of the invention is to provide a device of this character which shall be simple of construction, durable in use, and comparatively inexpensive of production and by means of which a single or a plurality of knives may be thoroughly and expeditiously scoured at a minimum expenditure of labor.

With this and other objects in view the invention consists in certain features of construction and combination of parts, which will be hereinafter fully described and claimed.

In the accompanying drawings, Figure 1 is a perspective view of my improved knife-scourer, showing in dotted lines the knives supported in position. Fig. 2 is a longitudinal vertical sectional view. Fig. 3 is a fragmentary sectional view at right angles to Fig. 2. Fig. 4 is a detail perspective view of one 30 of the knife-rubbers.

In the accompanying drawings the same reference characters indicate the same parts of the invention.

1 denotes a suitable casing consisting of the 35 side pieces 2, the end pieces 3, and a removable bottom 4, the said bottom being provided with lugs 5, by means of which the device may be screwed to a table, bench, or other support. The bottom 4 of the casing is preferably inclined on its upper face and slants to an opening 6 in the lower end of one of the end pieces 3 of the casing, closed by a slide 7.

8 denotes a series of vertically-disposed rubbers, each of which consists of a block 9, made 45 of any suitable material, such as wood or metal, and covered with a soft rubbing-strip 10, preferably of leather. The upper end of each block is provided with a curved head 11 to facilitate the introduction of the blades of 50 the knives between said blocks, and they further provided with shoulders 12, which take

under the longitudinal inwardly-projecting flanges 13, formed at the upper end of the side pieces of the casing, thus preventing the accidental withdrawal of said rubbers.

14 denotes bars fixed within the casing and provided with plate-springs 15, the energy of which is exerted to force the rubbers together. I prefer to fasten the middle rubber in fixed position to the casing, so that each spring 60 will act against the movable rubbers arranged between said spring and the stationary rubber, whereby a more positive action is secured in the operation of the machine when but one or two knives are being cleaned. The lower 65 ends of all the rubbers are provided with a notch or recess 16, which forms a longitudinal channel from end to end of the casing immediately above the inclined bottom to permit of the emery or other abrading or cleaning agent after it has been used and sifted to the bottom of the casing to be removed through the opening 16 and be reused.

17 denotes the knife-supporting frame, which comprises the side pieces 18, which are 75 adapted to slide between the end pieces of the casing and the bars 14 and are provided with vertical grooves 19, into which project screw-stops 20 to limit the vertical movement of said frame by coming in contact with the 80 end walls of said grooves. The upper end of the frame is provided with a grip or handle 21, by means of which the frame is reciprocated. A horizontally-disposed bar 22 is connected to the side pieces of the frame intermediate their ends and is provided with apertures 23 for the introduction of the knife-blades between the rubbers.

24 denotes a comb-plate, the spaces between the teeth of which are aligned with the apertures in the cross-piece. This comb-plate is provided with studs 25, which are journaled in bearings 26, secured to the side pieces of the knife-supporting frame, thus permitting the plate to be swung from over the cross-piece.

27 denotes means for fastening the comb-plate in operative position. This means consists, preferably, of turn-buttons; but any other suitable fastenings may be used in lieu thereof.

When it is desired to scour knives, the

comb-plate is swung to one side to permit of the introduction of the knife-blades through the apertures in the cross-bar 22 down between the scrubbers. After the knives have 5 been thus placed the comb-plate is swung over the cross-bar 22, with the fingers of said comb-plate engaging the bolsters of said knives. The turn-buttons 27 are now swung down into engagement with the comb-plate, 10 thus locking the bolsters of said knives between the comb-plate and the cross-bar. The handle 21 is now grasped, and by reciprocating the knife-supporting frame vertically the blades of the knives will be quickly 15 and thoroughly scoured. Those portions of the blades immediately below the bolsters which are not scoured by the rubbers may be scoured by the rubber-strip 28, attached to one corner of the casing. 20 The emery or other cleaning agent is sprinkled upon the tops of the upper ends of the rubbers, works down between the sides of the same, and finally down upon the bottom of the casing. By tapping the casing the emery will be shaken to the lower end of the inclined bottom and may be removed through the slide at that end to be reused. 25 From the foregoing description, taken in connection with the accompanying drawings, 30 the construction, operation, and advantages of my improved knife-scourer will be readily apparent without requiring an extended explanation.

It will be seen that the device is simple of 35 construction, that said construction permits of its manufacture at small cost, and that it

is exceedingly well adapted for the purpose for which it is designed.

It will of course be understood that various changes in the form, proportion, and the minor details of construction may be resorted to without departing from the principle or sacrificing any of the advantages of this invention. 40

Having thus described the invention, what 45 is claimed, and desired to be secured by Letters Patent, is—

1. In a knife-scourer the combination with the casing provided with an inclined bottom and provided with a discharge-opening at one 50 end, and spring-actuated rubbers mounted in said casing; of a reciprocatory knife-supporting frame mounted to slide in said casing, substantially as and for the purpose set forth. 55

2. In a knife-scourer the combination with the casing and rubbers mounted therein and adapted to engage the knife-blades; of a reciprocatory knife-supporting frame mounted to slide in said casing, said frame being 60 provided with a cross-bar formed with openings, a comb-plate carried by said frame, and means for clamping the comb-plate against the bolsters of the knives to be scoured, substantially as and for the purpose set forth. 65

In testimony whereof I have hereunto set my hand in presence of two subscribing witnesses.

THOMAS BEAMONT ABBOTT.
